[57] CLAIM

The ornamental design for a battery operated pencil sharpener, as shown and described.

DESCRIPTION

FIG. 1 is a prespective view, as viewed from the front, of a battery operated pencil sharpener, showing my new design; FIG. 2 is a rear elevational view thereof; FIG. 3 is a top plan view thereof; FIG. 4 is a left side elevational view thereof; FIG. 5 is a right side elevational view thereof; and, FIG. 6 is a bottom plan view thereof.

The structure depicted by means of broken lines in FIG. 6 has been shown for illustrative purposes only and forms no part of the claimed design.
